UNITED STATES PATENT OFFICE.

THEODORE W. LITTLE, OF BROOKLINE, MASSACHUSETTS, ASSIGNOR TO WALWORTH MANUFACTURING COMPANY, OF BOSTON, MASSACHUSETTS, A CORPORATION OF MASSACHUSETTS.

WRENCH.

1,271,734.

Specification of Letters Patent.

Patented July 9, 1918.

Application filed January 9, 1915. Serial No. 1,450.

To all whom it may concern:

Be it known that I, THEODORE W. LITTLE, of Brookline, in the county of Norfolk and State of Massachusetts, a citizen of the 5 United States, have invented a new and useful Improvement in Wrenches, of which the following is a specification.

My invention relates especially to that type of wrenches well known as Stillson wrenches, and it consists in an arrangement whereby the main shank and body of the wrench or housing can have only a limited movement with relation to each other so that the movable parts will always remain in operative 10 relation and other resulting advantages attained later to be referred to.

The essential object of my invention is to take up and distribute to the best advantage strain put upon the wrench for preventing 20 breakage, twisting or bending of the operating parts and wear thereon.

My invention will be understood by reference to the drawings in which—

Figure 1 is a side view of a wrench embodying my invention.

Fig. 2 is a longitudinal section through the working parts thereof.

Fig. 3 is a section on the line 3—3 of Fig. 2, and

Fig. 4 is a top view of the removable jaw.

Fig. 5 is a side elevation of the wrench in action.

Referring to the drawings, A represents the main shank of the wrench provided at 35 one end with a suitable handle A¹ and at its opposite end with a jaw E fixed to the shank though preferably detachably secured to it by a pin e. The main shank A is also preferably provided, as is customary, with 40 a lateral projection affording a shoulder a.

C is the movable shank of the wrench carrying a jaw C¹. This shank is notched or threaded as at c in the usual manner.

Embracing the shanks A and C and pivoted to the main shank at b is a housing B. This housing is of the usual type and comprises passages separated by a partition b³, and of which passages B¹ is that through 50 which the main shank A extends and B² the one through which the movable shank C extends.

Engaging the movable shank and mounted within the housing is an adjusting nut D.

The housing has the usual side openings to 55 permit of the nut projecting beyond its sides

whereby the nut may be turned upon the threads c of the movable shank to adjust its jaw C¹ in relation to the jaw E fixed to the main shank. In connection with the retention of the adjusting nut it will be observed, 60 especially by reference to Fig. 2, that the nut is held within the housing against else than a rotary movement by its fitting within a chamber comprising the recess d in the end wall of the housing, the sides of the housing 65 or portions thereof which frame the openings therein, and between the partition b³ in the housing and the shoulder a of the main shank A.

On the jaw E of the main shank are a 70 pair of rigid arms E¹ which extend well over the movable shank and directly abutting the housing in front of the adjusting nut. These arms provide, as will be more fully explained, stops with which the housing has 75 engagement in the operation of the wrench for limiting the rocking movement thereof on its pivot, and take up directly the pressure of the nut and prevent lateral rocking or twisting of the housing with respect to 80 the main shank. The arms are preferably made quite wide and snugly embrace the movable shank whereby they may assist in the lateral support of this shank.

The wrench is shown preferably provided 85 with the usual springs b¹, b² attached to the opposite sides of the main shank and bearing against the opposite inner walls of the passage B¹ of the housing.

The operation is as follows: The normal 90 position of the parts is substantially as shown in Fig. 1. After the jaws have been brought into engagement with the work the ensuing pressure tends, as the jaws bite into the work, to draw the movable jaw forward 95 over the fixed jaw; at the same time the strain tends to throw the movable jaw outwardly away from the fixed jaw and to draw the movable shank out of the housing. The draw upon the movable shank is transmitted 100 to the nut, which draws against the housing, and the resulting tendency is to turn the housing upwardly around its pivotal connection, which turning of the housing is determined or limited by the engagement of 105 the top of the housing with the arms E¹, which operate as stops for limiting the rocking movement of the housing on its pivot. The arms E¹, thus limiting the rocking movement of the housing, act also to take up 110

the pressure exerted by the adjusting nut or assist in taking up such pressure if the shoulder a is employed. At the time stress is first exerted upon the work the top surface of the nut will bear against the shoulder a on the main shank and also against the housing. Upon the turning of the housing the top surface thereof will engage the arms E^1 . Both these arms and the shoulder a will then take up the pressure on the nut. In this connection it will be observed that the resistance offered by the arms E^1 is a resistance directly within the line of stress exerted upon the movable shank to withdraw the nut and where such resistance will be most effective for taking up the pressure of the nut. The arms E^1 might well bear all the pressure of the adjusting nut and the shoulder a be entirely eliminated. The shoulder a is preferably retained in order to provide as much surface for taking up the pressure of the nut as possible. With the shoulder a retained any tendency for the adjusting nut to slip off the shoulder as the housing becomes turned is prevented by the arms E^1 which prevent any such excessive turning of the housing as would permit of such slippage.

By reason of the direct and broad abut-

ment presented by the arms to the housing, strain is practically taken off the housing in the operation of the wrench and lateral rocking or twisting of the housing, which might otherwise tend to disrupt it, prevented.

As previously described, the arms E^1 are preferably made quite wide and snugly embrace the movable shank and accordingly are especially effective in preventing lateral twisting of the movable shank.

What I claim as my invention is:

In a wrench, the combination with a main shank carrying a jaw, a threaded movable shank carrying a jaw, a housing embracing said shanks and pivoted to the main shank and an adjusting nut engaging the movable shank and mounted in the housing, of a pair of rigid arms on the jaw of the main shank extending well over the movable shank and directly abutting the housing in front of the nut whereby to limit the rocking movement of the housing on its pivot and take up directly the pressure of the nut in operation and prevent lateral rocking or twisting of the housing with respect to the main shank.

THEODORE W. LITTLE.
